PAPER-MAKING MACHINE.

SPECIFICATION forming part of Letters Patent No. 417,546, dated December 17, 1889.

Application filed January 21, 1889. Serial No. 297,012. (No model.)

To all whom it may concern:

Be it known that I, FRANCIS ASBURY CUSHMAN, a citizen of the United States, residing at Plymouth, in the county of Grafton and State 5 of New Hampshire, have invented certain new and useful Improvements in Paper-Making Machines; and I do declare the following to be a full, clear, and exact description of the invention, such as will enable others skilled 10 in the art to which it appertains to make and use the same, reference being had to the accompanying drawing, and to the letters of reference marked thereon, which form a part of this specification.

15 The object of my invention is to dispense with a felt entirely and take the pulp directly off from the wire apron, as shown, after which it is transferred to the lower press-roll.

A further object is to remove as much as 20 possible of the water from the pulp before it reaches the suction-roll shown, and by means of a revolving brush located below the wire apron.

My invention will be described below, and 25 pointed out in the claims.

The drawing shows a perspective view of a paper-making machine constructed in accordance with my invention, parts being broken and no frame-work being shown except a portion in connection with the press-rolls.

Like letters refer to like parts. In a machine constructed in accordance with my invention the usual tube-rolls, the 35 tube-roll frame, the suction-boxes, and the dandy-roll are not necessary and are omitted, the machine as far as the first press-rolls consisting merely of the parts shown in the drawings, suitably supported in a frame.

40 A is a stuff-vat, and B is a chute, the design being to have the pulp to come upon the upper face of the wire apron from an elevation. The chute may come nearly down to the apron, or the mouth of the chute may be some distance above, as indicated by dotted line *r r*, so as to give the water a chance to leave the pulp somewhat before the latter comes upon the apron.

45 D and E are the apron-supporting rolls, and 50 C is the wire apron, which may be of the de-

sired width. Where the apron is several feet long, I may employ supporting-rolls *a a*.

In order to further remove the water from the passing pulp which has not already passed

through the meshes of the apron, I arrange a 55 revolving brush J below said apron, giving

the brush revolution by a pulley and band, as shown, or in any suitable way. This brush

should be of the proper flexibility not to dis- 60

turb the pulp on the upper side of the apron and throw it backward. In practice I have

found that the brush alone will accomplish

the purpose desired and assist in keeping the meshes of the apron open, flinging the water

rapidly away; but, if desired, a small press- 65

roll K may be placed directly over the brush and above the apron, the object being to press

the pulp somewhat at this point and aid in

removing the water in connection with the

brush. At a point where the apron passes 70

well over the roll E, I arrange a suction couch- 75

roll F, of any proper construction, from which

the pulp-water may pass to the exit-pipe *b* in

the common way. This roll exhausts much

or nearly all of the remaining water from the

pulp, and takes the latter directly from the

apron to its perforated surface, after which it

transfers it to the lower press-roll G, from

which the pulp passes to the upper press-roll

H, where it may be removed in the usual way

80 in sheets, it being understood that that portion of the couch-roll at which the web leaves

it is cut off from the suction or exhaust portion, in order that the web may pass freely

from the couch-roll to the lower press-roll. By

85 the mechanism shown I have brought the pulp

to the roll H in a remarkably dry state when

the rolls D and E were but from five to seven

feet apart, which permitted the use of a very

90 short apron, the usual apron being many feet

longer, and no supporting-rolls *a a* were re-

quired, the brush J performing such function

in addition to that of removing water.

I am aware that suction devices have been

placed beneath the apron, but am not aware

95 of a suction-roll located to take the pulp from

the upper face of the apron and transfer it

like mine.

Having fully described my invention, what

I claim is—

1. The combination, with the outer face of the wire apron, of a suction-roll removing the pulp from the apron directly, and a device, substantially as shown, for receiving the pulp transferred from said suction-roll, as set forth.
  2. The combination, with the apron, of the suction-roll bearing on the outer face of the former, and the lower and upper press-rolls, as set forth.
  3. The combination, with the apron, rolls for carrying it, and a suction-roll bearing on the outer face of said apron, of a revoluble
- brush in contact with the under face of the apron, as and for the purposes set forth.
4. The combination, with the wire apron, of a brush located under said apron and a press-roll located above the apron and said brush, as and for the purpose set forth.

In testimony whereof I affix my signature in presence of two witnesses.

FRANCIS ASBURY CUSHMAN.
